Primary Examiner — Cynthia M. Chin(74) *Attorney, Agent, or Firm* — Barnes & Thornburg LLP(57) **CLAIM**

I claim the ornamental design for a wagon trailer, as shown and described.

DESCRIPTION

FIG. 1 is a front perspective view of the wagon trailer according to the new design.

FIG. 2 is a front elevation view of the wagon trailer shown in FIG. 1.

FIG. 3 is a rear elevation view of the wagon trailer shown in FIG. 1.

FIG. 4 is a left side elevation view of the wagon trailer shown in FIG. 1.

FIG. 5 is a right side elevation view of the wagon trailer shown in FIG. 1.

FIG. 6 is a top plan view of the wagon trailer shown in FIG. 1; and,

FIG. 7 is a bottom plan view of the wagon trailer shown in FIG. 1.

The broken lines in the drawings illustrate portions of the wagon trailer that form no part of the claimed design.
